Stove with Box containing Water.

Zina Phinney
Letters Patent

1825X

The Schedule referred to in these Letters Patent and making part of the same containing a description in the words of the said Zina Phinney of herself, of his improvement in the tanning of flocks.

1st A Box of sheet wrought or cast iron placed on a stove with the outer edges closed over the stove, with a pipe or conductor to convey the heat to any part of that or another room, or into an oven. The same box may be placed in the fire, with the addition of a bottom, the opposite end from the pipe being left open suitable for a draught.

2^d This Box may be used for heating ovens of any description, or for kiln drying corn, and will be found particularly useful in baking for cornmeal in camp, also in placing the same in thin yards, and conveying the pipe through the rats, the business of tanning will be greatly facilitated in cold water.

3^a The said Box being filled with chips, or fuel and by closing the draught will afford sufficient light for a room by setting the smoke on fire at the end of the pipe. A common stove may be used in the same way and the coals saved after the smoke is evapored, and the same Box made to hold water will produce steam sufficient for cooking.

4th The Box being supplied with tar with a tube containing a lighter which will afford a good light. a pipe should be suspended to carry off the smoke.

Witnesses.
